FIG. 5

FIG. 4

FIG. 1 is a side elevational view of a vehicle marker lamp embodying our new design;

FIG. 2 is a top plan view thereof;

FIG. 3 is a front elevational view thereof; and

FIG. 4 is a bottom plan view thereof; and

FIG. 5 is a transverse sectional view taken on the line 5-5 of FIG. 3 and illustrating the configuration of the outer end of the lens of said lamp.

We claim:

The ornamental design for a vehicle marker lamp, as shown.
